CLAIM

The ornamental design for a temperature therapy device, as shown and described.

DESCRIPTION

FIG. 1 is a top perspective view of a temperature therapy device;

FIG. 2 is a front view of the temperature therapy device;

FIG. 3 is a rear view of the temperature therapy device;

FIG. 4 is a right side view of the temperature therapy device;

FIG. 5 is a left side view of the temperature therapy device;

FIG. 6 is a top view of the temperature therapy device;

FIG. 7 is a bottom view of the temperature therapy device;

and,

FIG. 8 is a bottom perspective view of the temperature therapy device.

The broken lines shown in the Figures illustrate portions of the temperature therapy device that form no part of the claimed design.

1 Claim, 6 Drawing Sheets
